UNITED STATES PATENT OFFICE.

HERBERT G. KAMRATH, OF FLINT, MICHIGAN, ASSIGNOR TO A. C. SPARK PLUG COMPANY, OF FLINT, MICHIGAN, A COMPANY OF MICHIGAN.

AIR CLEANER.

Application filed May 11, 1925. Serial No. 29,373.

The object of this invention is to improve air cleaners by the provision of a novel form of dust collecting means. I have found one application for my invention in the construction of an air cleaner of the centrifugal type for use in connection with automobile carburetors. This type of cleaner usually consists of a receptacle provided with an air inlet and an air outlet which are so related as to effect either sharp changes in direction or a continuous change in direction of the air stream so as to separate the particles of dust therefrom by virtue of their greater inertia which tends to cause them to continue in their previous course after the air itself has shifted its direction. This results in throwing these particles against the sides of the receptacle and my invention consists in so covering or treating these surfaces of the receptacle as to cause the dust to adhere thereto thus effecting its separation from the air stream. The surfaces may be cleaned and retreated or re-covered at intervals.

Referring now to the drawing:

Figure 1 is a side elevation of a conventional automobile engine with my improved cleaner attached thereto;

Figure 2 is a longitudinal sectional view of my cleaner; and

Figure 3 is an end elevation of the cleaner. Figure 1 shows my air cleaner 2 attached to the air inlet of the carburetor 4 of the engine 6. It will be noted that the intake of my cleaner faces in a direction opposite to the direction of the blast from the fan 7 and also opposite to the direction of motion of the vehicle so that there is to a certain extent a selection of clean air before the air actually enters the cleaner.

The cleaner here shown consists of a casing or receptacle 8 having secured therein at one end an air directing member 10. The member 10 is roughly of cone shape, is centrally apertured, and is provided with radiating spiral fins or blades 12. It will be noted that the inner ends of the blades 12 are spaced from the axis of the casing 8 by a distance greater than the radius of the air discharge port constituted by the aperture in the member 10, the hub 10' of the member 10 constituting in this instance the spacing means. 14 indicates an air straightener which is indeed nothing but a second air directing means. The straightener 14 is provided with a screw threaded shank 16. In assembling the clean-

er the member 10 is slipped into the open end of the casing 8, the extent of its insertion being limited by the engagement of the casing 8 with a flare formed on the member 10 and shown at 11. The straightener 14 is then inserted, shank first, into the central aperture in the member 10, the shank passing outwardly through a hole 18 in the end of the casing 8 where it receives a thumb nut 19. The straightener 14 is provided with shoulders 20 which engage the member 10 so that upon tightening the nut 19 the parts are clamped firmly together.

The operation of the device so far described is as follows: The air striking the blades 12 is given a spiral motion which throws the particles of dust carried with it to the wall of the casing 8. Upon reaching the end of the casing the air, which has now been relieved of the greater portion of its dust, reverses its direction and returns, spiral fashion, until it strikes the straightener 14 which has a portion curved to correspond to the direction of rotation of the air stream followed by a straight portion which serves to straighten the stream of air prior to its passage through the carburetor and intake manifold.

It is obvious that means must be provided to take care of the dust which collects in the casing 8 else when a sufficient quantity accumulates the whirling air will stir it up and carry it along into the carburetor. My method of taking care of this difficulty is to provide the interior of the casing 8 with a covering which will serve to retain the dust. Thus I may use a lining of fibrous material among the fibers of which the dust particles will be held; or I may coat the interior of the casing 8 with a material such as oil, grease, or adhesive, to which the dust particles will adhere. I have chosen to illustrate the use of both expedients although it is obvious that either may be applied alone if desired. Thus I have shown the container 8 provided with a lining 22 of some fabric or felted material and have preferably applied to it a coating 23 of oil, grease, or the like. It will now be seen that the particles of dust thrown into contact with the casing wall will be retained there. Upon a sufficient accumulation of dust the lining or the coating, or both, may be renewed whereupon the cleaner will be restored to its original condition.

While I have shown my invention in con-

nection with one specific type of cleaner it is to be understood that it is not limited to use therewith but is capable of serving with equal effectiveness in many other relations.

5 I claim:

1. The combination of a cylindrical receptacle having an open end, an annular series of spirally arranged air directing blades in said end of the receptacle for imparting a whirling motion to the entering air stream in a direction lengthwise of the axis of the receptacle, a centrally arranged air discharge port for said receptacle, the interior of the receptacle being coated with dust retaining material,
- 10 10 said air directing blades extending inwardly from the periphery of the receptacle to points removed from the axis of the receptacle a dis-
- 15

tance greater than the radius of the air discharge port.

2. In combination with a fan, an air cleaner comprising a casing having an air admission opening facing away from the fan so that the heavier particles of dust in the air stream are carried beyond said opening by virtue of their greater inertia, means for imparting a whirling motion to the air stream entering said casing, a clean air discharge port in said casing, the interior of the casing being provided with a coating of dust retaining material to catch particles of dust thrown out- 30 wardly by the whirling air stream.

In testimony whereof I affix my signature.

HERBERT G. KAMRATH.
